(57) **CLAIM**

The ornamental design for a film scanner, as shown and described.

DESCRIPTION

FIG. 1 is a top, front, left side isometric view of a film scanner showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top, front, right side isometric view thereof;

FIG. 9 is a rear, top, right side isometric view thereof;

FIG. 10 is a rear, top, left side isometric view thereof;

FIG. 11 is a bottom, front, left side isometric view thereof;

FIG. 12 is a bottom, rear isometric view thereof;

FIG. 13 is a top, front, left side isometric view of the film scanner shown in FIG. 1 in an alternate configuration with the screen folded down;

FIG. 14 is a front elevational view thereof;

FIG. 15 is a rear elevational view thereof;

FIG. 16 is a right side elevational view thereof;

FIG. 17 is a left side elevational view thereof;

FIG. 18 is a top plan view thereof;

FIG. 19 is a bottom plan view thereof;

FIG. 20 is a top, front, right side isometric view thereof;

FIG. 21 is a rear, top, right side isometric view thereof;

FIG. 22 is a rear, top, left side isometric view thereof;

FIG. 23 is a bottom, front, left side isometric view thereof;

FIG. 24 is a bottom, rear isometric view thereof;

FIG. 25 is a top, front, left side isometric view of the film scanner shown in FIG. 1 in an alternate condition of use;

FIG. 26 is a front elevational view thereof;

FIG. 27 is a rear elevational view thereof;

FIG. 28 is a right side elevational view thereof;

FIG. 29 is a left side elevational view thereof;

FIG. 30 is a top plan view thereof;

FIG. 31 is a bottom plan view thereof;

FIG. 32 is a top, front, right side isometric view thereof;

FIG. 33 is a rear, top, right side isometric view thereof;

FIG. 34 is a rear, top, left side isometric view thereof;

(Continued)

FIG. 35 is a bottom, front, left side isometric view thereof; and,

FIG. 36 is a bottom, rear isometric view thereof.

The subject matter shown in broken line depicts portions of the film scanner in which the design is embodied and environmental structure that form no part of the claimed design.
